US00D887371S

(12) **United States Design Patent** (10) Patent No.: **US D887,371 S**
(45) Date of Patent: ** *Jun. 16, 2020

(54) **CONTROL DEVICE**

(71) Applicant: **Lutron Technology Company LLC**,
Coopersburg, PA (US)
(72) Inventors: **Elliot G. Jacoby**, Glenside, PA (US);
Jason C. Killo, Emmaus, PA (US);
Brad Michael Kreschollek, Bethlehem,
PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/684,650**

(22) Filed: **Mar. 22, 2019**

Related U.S. Application Data

(63) Continuation of application No. 29/615,437, filed on Aug. 29, 2017, now Pat. No. Des. 856,940, which is a continuation of application No. 29/570,643, filed on Jul. 11, 2016, now Pat. No. Des. 803,167, which is a continuation of application No. 29/529,486, filed on Jun. 8, 2015, now Pat. No. Des. 767,513, which is a continuation of application No. 29/472,772, filed on Nov. 15, 2013, now Pat. No. Des. 734,277.

CLAIM

We claim the ornamental design for a control device, as shown and described.

DESCRIPTION

FIG. 1 is a perspective view of a control device showing our new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The rear views form no part of the design and are omitted. The portions of the drawings appearing in broken lines are for environment only and do not form part of the claimed design.

1 Claim, 4 Drawing Sheets
